Inventor

Emil Kyhl

G. Kennedy,
Attorney

UNITED STATES PATENT OFFICE.

EMIL KYHL, OF BRITT, IOWA.

STARTING SWITCH FOR ELECTRIC STARTING MOTORS.

Application filed December 3, 1925. Serial No. 72,972.

My invention relates to improvements in starting switches for electric starting motors, and the object of my improvement is to supply an adjustable, simple and effective device of this class, constructed for permanent usefulness in service.

This object I have accomplished by the means which are hereinafter described and claimed, and which are illustrated in the accompanying drawings, in which Fig. 1 is a side elevation of an electric starting motor, such as is employed for starting the vehicle engine particularly for Ford motor cars, and showing partly in elevation and partly in section my improved starting switch therefor. Fig. 2 is a full size elevation of the switch taken at an angle of ninety degrees relative to the elevation of said Fig. 1, and having parts taken on central vertical section. Fig. 3 is a face elevation of a propelling finger or pusher adapted for use in actuating the trigger element of my device in one direction.

The numeral 1 denotes a conventional electric starting motor, parts or accessories not being shown, but which has one electric terminal 2, projecting without and exteriorly threaded. On the projecting part of this terminal is mounted an adjusting nut 7 to adjustably support an apertured angular member 8 made of elastic plate as of steel. The terminal part 2 traverses the aperture in the member 8 and has a lock-nut 5 mounted thereon above and contacting with the member 8 to tightly lock this member to project laterally from the terminal. For a purpose to be described, the terminal 2 has an extension member 3 the lower part of which is exteriorly threaded to take a nut 4, and the upper end of the threaded terminal 2 also is meshed in this nut 4, whereby the said extension member 3 is mounted on the terminal 2 for longitudinal adjustments relative thereto. As shown in Fig. 1, the member 8 has its aperture 6 longitudinally lengthened so that the nuts 5 and 7 may hold the member 8 in an adjusted position laterally upon the terminal 2.

An oblong plate 9 of elastic insulation is fastened on the upwardly-directed part of the angular member 8. A bar 10 has its lower end fastened on the upper part of the insulation plate and then is bent slopingly over the upper end of the terminal part 3 and then bent again slopingly upwardly, and is used as a trigger member, at 11.

The insulation plate 9 is medially transversely apertured to seat a threaded member 13 therethrough secured by the nuts 14 and 16 on opposite sides for adjustment laterally relative to the plate 9 and so that the member 13 as an electric terminal may be positioned angularly relative to the other terminal part 3 and to be shifted into make and break contact therewith by means to be described. The cable conductor 15 is end-clipped between the plate 9 and the nut 16.

The numeral 17 denotes a trigger pusher bar, positioned substantially vertically to contact at its lower end with one face of the trigger 11 just above its angular bend. The pusher plate or bar 17 is crimped slopingly or obliquely at its upper end in registration with a like crimp 22 on a smaller clamping-plate 18, and the latter is fastened by bolts 20 and nuts 19 to the bar 17 to clamp therebetween one end of a rod 21, the upper part being broken away but which in extension to the dashboard of a car, may be manipulated to cause the pusher 17 to push in one direction against the trigger 11 to shift or rock this member together with the elastic insulation 9 and member 8 to make and break contact of the terminals aforesaid.

This switch device is very quickly responsive and reactive in use and the elastic elements cannot become warped or bent out of line, and the different adjustments shown are used to true up the contacts as necessary. By this means the sparking can be exactly retarded or advanced, as necessary in the well-known use of the starter 1 on Ford cars.

Having described my invention, what I claim as new, and desire to secure by Letters Patent, is:

1. A device of the character described, comprising an electric terminal, an elastic plate of insulation bracketed on said terminal, another electrical terminal mounted on said insulating device at an angle to the first-mentioned terminal, and a reciprocable member movable for laterally shifting said insulating device to effect contact between said terminals.

2. A device of the character described, comprising an electric terminal, an elastic insulating plate mounted on said terminal removably and for lateral adjustment relative thereto, another electric terminal mounted for lateral adjustment on said insulating device at an angle to the first-mentioned terminal, a trigger fixed terminally

on said plate, and means for laterally shifting said trigger and insulating plate to effect contact between said terminals.

3. A device of the character described, comprising a two part electric terminal whose parts are movably connected for relative longitudinal adjustment, an angular member one limb of which is bracketed to extend laterally from the lowermost part of 10 said terminal, an insulating plate mounted angularly on said angular member, said angular member and said insulating plate being elastic, an angular trigger mounted terminally on said plate, and another electric terminal mounted on said insulating plate angularly relative to the first-mentioned terminal and adapted when said trigger is moved in one direction to be shifted into 15 lateral contact with the uppermost part of 20 the first-mentioned terminal, and to break contact therewith.

4. A device of the character described, comprising a two-part electrical terminal whose parts are adjustably connected, means for holding them in adjusted positions, a 25 bracket adjustably mounted on and for adjustments to and from said terminal, an elastic insulating plate mounted on said bracket, a bent trigger member mounted terminally upon said insulating device, another electric terminal adjustably mounted on said insulating device angularly relative to the upper part of the two-part terminal to be shifted into contact therewith by movement laterally thereagainst, and a shifting 30 rod having a removable pressure finger loosely engaging one face of said trigger member to releasably force the second terminal into contact with the first terminal.

In testimony whereof I affix my signature.

EMIL KYHL.
